United States Patent Office

Des. 218,159
Patented July 28, 1970

218,159

OFFICE CHAIR

Bent Harlang, 21 Sigridsvej, Hellerup, Denmark, and
Jorgen Rasmussen, Gl. Haltegaard, Holte, Denmark

Filed Sept. 18, 1968, Ser. No. 13,598

Claims priority, application Denmark Mar. 20, 1968

Term of patent 14 years

Int. Cl. D6—01

U.S. Cl. D15—1

Fig. 1.

Fig. 2.

Fig. 3.

Fig. 4.

FIG. 1 is a perspective view of the design for an office chair;

FIG. 2 is a perspective view of the office chair, looking from the back towards the front thereof;

FIG. 3 is a front elevational view of the office chair shown in FIGS. 1 and 2; and

FIG. 4 is a perspective view of the office chair with the chair lying on its side to more clearly illustrate the design of the legs thereof.

We claim:

The ornamental design for an office chair, as shown.
